(57) **CLAIM**

The ornamental design for a support device as shown and described.

DESCRIPTION

FIG. 1 is a front, right, and top perspective view of the first embodiment of a support device, showing my new design; FIG. 2 is a rear, left, and bottom perspective view thereof; FIG. 3 is a front elevational view thereof; FIG. 4 is a rear elevational view thereof; FIG. 5 is a left elevational view thereof; FIG. 6 is a right elevational view thereof; FIG. 7 is a top plan view thereof; FIG. 8 is a bottom plan view thereof; FIG. 9 is a front, right, and top perspective view thereof, illustrated in another configuration; FIG. 10 is a front, right, and top perspective view of the second embodiment of a support device, showing my new design; FIG. 11 is a rear, left, and bottom perspective view thereof; FIG. 12 is a front elevational view thereof; FIG. 13 is a rear elevational view thereof; FIG. 14 is a left elevational view thereof; FIG. 15 is a right elevational view thereof; FIG. 16 is a top plan view thereof; FIG. 17 is a bottom plan view thereof; and, FIG. 18 is a front, right, and top perspective view thereof, illustrated in another configuration.

The broken lines in the drawings depict portions of the support device and form no part of the claimed design.

1 Claim, 18 Drawing Sheets
